(57) **CLAIM**

The ornamental design for a liquid chromatography device, substantially as shown and described.

DESCRIPTION

FIG. 1 is a perspective view of a liquid chromatography device in accordance with the present design;

FIG. 2 is a front or back view (i.e., symmetrical) thereof;

FIG. 3 is a top view thereof;

FIG. 4 is a side view (i.e., left or right view, due to symmetry) thereof;

FIG. 5 is a bottom view thereof;

FIG. 6 is a perspective view of another liquid chromatography device in accordance with the present design formed of transparent or translucent materials;

FIG. 7 is a front or back view (i.e., symmetrical) thereof; and,

FIG. 8 is a side view (i.e., left or right view, due to symmetry) thereof.

The dash-dash broken lines in the drawings show elements of the device that form no part of the claimed designs.
